UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

COMBINED LAMP SOCKET AND CURRENT TAP.

Application filed May 19, 1925. Serial No. 31,438.

The invention relates to a combined lamp socket and current tap.

The object of the present invention is to provide a simple, durable and comparatively inexpensive combined lamp socket and current tap having an insulating body constructed of a single piece of molded insulating material and equipped with double spring contacts which are located in the insulating body by the terminal conductor bars in assembling the parts of the device.

A further object of the invention is to provide a combined lamp socket and current tap provided with means for receiving a plug for enabling the insulating body which is equipped with projecting terminal fingers or blades to be converted into a screw plug socket when desired.

With these and other objects in view, the invention consists in the construction and novel combination and arrangement of parts hereinafter fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a longitudinal sectional view of a combined lamp socket and current tap constructed in accordance with this invention.

Fig. 2 is a side elevation of the same.

Fig. 3 is an edge view showing one of the laterally extending cylindrical extensions in end view.

Fig. 4 is a horizontal sectional view on the line 4-4 of Fig. 1.

Fig. 5 is a reverse plan view of the lamp socket and current tap.

Fig. 6 is a plan view of the screw shell contact.

Fig. 7 is a detail view of one of the internally threaded bushings.

Fig. 8 is a detail perspective view of one of the double transverse spring contacts.

Fig. 9 is a plan view of the upper insulating disk.

Fig. 10 is a similar view of the lower insulating disk.

In the accompanying drawings in which is illustrated the preferred embodiment of

the invention 1 designates an insulating body consisting of a single piece of molded material and composed of a solid upper portion having laterally extending cylindrical enlargements 2 and provided with a hollow cylindrical lower portion 3, forming a socket for the reception of a screw shell contact 5 which is adapted to receive an electric lamp in the usual manner. The lower cylindrical portion is provided with an exterior bead 6 and exterior screw thread 7 and the upper solid portion is provided with spaced vertical apertures 8 and 9 for the reception of terminal conductor bars 10 and 11 which project beyond the upper end of the solid cylindrical portion and provide contact fingers or blades to fit in apertures of a screw plug or in an electric fixture for enabling the combined lamp socket and current tap to be electrically connected therewith. The solid upper portion of the insulating body has molded within it upper and lower interiorly threaded bushings 12 and 13 which are provided at their inner ends with a flange 14 forming a head and preferably corrugated as illustrated in Fig. 7 of the drawings to securely anchor the bushings within the insulating body and effectually prevent the bushings from becoming loose through the rotation of a screw or bolt for engaging the same with the bushings and in disengaging the screw or bolt therefrom. The solid cylindrical body is provided at the top with a reduced cylindrical extension 15 which is capped by a screw plug when applied to the present device. The blades or fingers 16 are tapered at their ends at 17 and are provided with oppositely flared apertures 18 to enable them to engage with protuberances or co-acting contact portions of a screw plug or other fixtures. The upper interiorly threaded bushing is adapted to receive a bolt for securing a screw cap or plug extension to the device and the lower bushing receives a screw 19 which pierces a center contact 20 and secures the same to the insulating body.

The terminal conductor bar 10 is provided at its lower end with an arm 21 arranged at right angles to the bar and located in a recess 22 in the top wall of the socket or compartment formed by the hollow cylindrical portion 3 of the body and secured by a rivet 23 to the flange 24 of the shell contact 5. This fastens the shell contact and the arm

of the conductor bar 10 and electrically connects the said parts as clearly indicated in Fig. 1 of the drawings. The other conductor bar 11 is provided at its lower end with an 5 arm 24' arranged at right angles to the conductor bar 11 and located in a recess 25 in the top wall of the socket of the said insulating body and pierced by the screw or bolt 19 and electrically connected by the same 10 to the center contact 20. An upper insulating disk 26 of grey fiber or other suitable material is fitted against the lower face of the arm 24 of the conductor bar 11 and is provided with a recess 27 to receive the arm 15 21 of the terminal conductor bar 10. The arm 21 of the conductor bar 10 is arranged in substantially flush relation with the upper disk 26 and a lower insulating disk 28 is interposed between the center contact and 20 the flange 24 of the shell contact 5. The center contact 20 is constructed of a single strip or piece of metal which is bent to form an upper attaching portion and a lower contact portion which is provided with a cup 25 shaped end 29. The lower contact portion is adapted to be bent out of the way in assembling the parts and in screwing the bolt 19 into the lower bushing and after the parts are assembled the lower contact portion of 30 the center contact is bent back into position and its resiliency will enable it to make proper contact with a lamp. The upper disk 26 and the flange 24 of the contact shell may be preferably provided with perforations 30 and 31 for the reception of a rivet 35 or other suitable fastening device for securing the said parts together to assist in assembling the device.

The upper solid portion of the insulating body is provided with spaced transversely disposed horizontal apertures 32 for the reception of double transversely disposed contact springs 33 each provided with a central approximately U-shaped bend 34 of angular 40 formation composed of parallel sides and a connecting portion arranged at right angles to the sides. The central bends 34 of the double contact springs form open-sided recesses which fit the terminal conductor bars 45 as clearly shown in Fig. 4 of the drawings and the contact springs are placed in position before the terminal conductor bars are assembled and when the terminal conductor bars are placed in the longitudinal apertures 50 of the insulating body they are passed through the central angular bends of the double contact springs and locate the same in the transverse openings 32 of the insulating body. The side portions of the double 55 contact springs are bent back upon themselves to provide resilient inwardly extending contact fingers 35 arranged at acute angle to the body portions of the springs at opposite sides of the central bend and provided with protuberances 36 for engagement

with terminal fingers or blades of a lamp socket or other fixture. The apertures 32 which extend entirely through the solid cylindrical upper portion of the insulating body are adapted to receive the said terminal fingers or blades of a lamp socket or the like at either end of the said transverse openings 32 and the double contact springs will enable a pair of such lamp sockets to be connected with the device at opposite sides of the same as will be readily understood in addition to receiving a lamp within its lower hollow cylindrical portion.

The end face of each lateral extending cylindrical enlargement 2 is recessed as shown 80 at 37 and the end face is provided with curved grooves 38 located within the recess 37 and connecting the transverse apertures 32 and adapted to enable a pair of blades or fingers to be readily engaged with the double 85 spring contacts. If the points of a pair of blades or fingers be placed in the grooves 38 a relatively rotary movement will carry the points into the apertures 32 so that there will be no trouble in engaging the blades or 90 fingers with the double contact springs of the transverse openings 32.

What is claimed is:

1. A device of the class described including an insulating body having spaced longitudinal openings and provided also with spaced transverse openings intersecting the longitudinal openings and communicating therewith and at their ends opening through said body, double contact springs arranged in the transverse openings, each consisting of a strip of flat material bent intermediate its ends to form an open-sided recess and straight alining portions extending in opposite directions from the open side of said recess, said oppositely directed portions being bent back upon themselves intermediate their ends to form resilient inwardly extending contact fingers arranged at acute angles to said oppositely directed portions and terminating adjacent the closed side of said recess and spaced therefrom, and conductor bars passing through said longitudinal openings and passing snugly through and conforming to the configuration of said open-sided recesses of the contact springs for clamping the closed side of the recess of each contact spring against the adjacent wall of the respective transverse opening whereby to secure the contact springs in relatively fixed 105 position in the insulating body.

2. A device of the class described including an insulating body consisting of a solid upper portion having laterally extending cylindrical enlargements, said body being also provided with a hollow cylindrical lower portion, the said upper portion being provided with spaced longitudinal openings and having horizontal openings extending longitudinally of the lateral extensions and 110 115 120 125 130

- opening through the ends of the latter, upper and lower bushings embedded in the upper portion of the insulating body, terminal conductor bars arranged in the longitudinal 5 openings and projecting from the upper end of the body and provided at their lower ends with arms, a contact shell secured to the arm of one of the terminal conductor bars, a center contact, a bolt piercing the center 10 contact and the arm of the other terminal conductor bar and engaging the lower threaded bushing, an upper insulating disk interposed between the shell contact and the arm which is secured to the lower bushing, 15 said disk being provided with a recess receiving the arm of the other terminal conductor bar, a lower disk interposed between the shell contact and the center contact, and contact springs arranged in the transverse 20 openings and engaged by the terminal conductor bars, and retained in place by the same.
3. A device of the class described including an insulating body having spaced longitudinal openings and provided also with spaced transverse openings intersecting the
- longitudinal openings and communicating therewith and opening at their ends through said body, a bushing embedded in the body between said transverse openings and spaced 30 therefrom, double contact springs arranged in the transverse openings and having terminal contact portions and provided between the contact portions with intermediate angular bends located at the longitudinal openings of the said body, conductor bars passing through the longitudinal openings and arranged in and conforming to the configuration of the said intermediate bends of the contact springs for locking the latter in the 35 transverse openings and each provided with an arm at its inner end, a center contact, a screw piercing the center contact and one of the said arms and having working fit with said bushing, a shell contact secured to the arm of the other conductor bar, and insulating disks arranged above and below the attached portion of the shell contact.
- In testimony whereof I have hereunto set my hand.

WILLIAM ILE.
